UNITED STATES PATENT OFFICE.

SAMUEL M. WHITE, OF ATLANTA, GEORGIA.

LACED SHOE.

Application filed June 5, 1924. Serial No. 718,137.

To all whom it may concern:

Be it known that I, SAMUEL M. WHITE, a citizen of the United States, residing at Atlanta, in the county of Fulton and State of Georgia, have invented certain new and useful Improvements in Laced Shoes, of which the following is a specification.

My invention relates to means for preventing the tongues of shoes of the open face laced type from slipping.

My invention consists in providing the tongue with a small hook arranged in the center at its upper end, so as to engage the shoe string when the right and left portions 15 of the shoe upper are drawn to closed position and the string tied.

One object of my invention is to provide an anti-slipping means for the tongues of shoes, in which said means can be applied 20 to the tongue in the course of the shoe's manufacture or after the shoe is offered to the trade.

A further object is to provide an anti-slipping means for the tongues of shoes, which can be applied to the tongue of any 25 shoe of open face laced type.

My invention is illustrated in the accompanying drawing, in which:

Fig. 1 is a perspective view of a shoe 30 having the usual tongue with my invention applied thereto.

Fig. 2 is a front view of a tongue, clearly showing the shoe string engaged by the hook in accordance with my invention.

Fig. 3 is a perspective view of a tongue 35 showing the preferred manner of applying my invention to a tongue having a lining.

The shoe 1 has the usual tongue 2, fastened at one end to the shoe in the customary way. This tongue 2 is provided at its up-

per portion with a hook 3 having its engaging member 3^a pointed toward the toe of the shoe 1. This hook 3 is arranged substantially at a point in the center of the tongue so as to engage the string 4 at its last crossing 4^a and 4^b, as the string is about to be inserted through the uppermost eyelets 5 and 5^a of the shoe 1. The hook 3 is riveted to the tongue as at 6 and is preferably arranged so that its clamped portion will be between 45 the inner surface of the tongue 2 and the lining 7.

It can be readily seen that I have provided an anti-slipping means, for shoe tongues that is inexpensive, easily applied to a shoe 50 tongue, and comfortable to the wearer.

What I claim is:

In a shoe of the open face lace type, a tongue to cover the opening in the front of the shoe, a lining on the inner side of said tongue, an inverted shoe lace hook having a flat head portion, a portion under the head and substantially parallel with the under side of the flat head, and rivet portion having its inner end flattened against the under 60 surface of the tongue, the hook providing a support for the shoe string, said hook being secured to the central portion of the tongue near its upper edge and arranged at a point 65 below the uppermost lacing eyelets of the shoe upper, so as to engage the shoe string at its last crossing before inserting the string in said eyelets of the shoe, the lining of the tongue covering the inner side of the rivet of the hook so as to prevent the hook 70 from irritating the leg.

In testimony whereof I hereunto affix my signature.

SAMUEL M. WHITE.
